UNITED STATES PATENT OFFICE.

GEORGE W. REAM, OF CANTON, OHIO, ASSIGNOR TO THE BUCHER & GIBBS PLOW COMPANY, OF SAME PLACE.

DESIGN FOR A PLOW-STANDARD.

SPECIFICATION forming part of Design No. 32,128, dated January 23, 1900.

Application filed December 2, 1899. Serial No. 739,056. Term of patent 14 years.

To all whom it may concern:

Be it known that I, GEORGE W. REAM, a citizen of the United States, residing at Canton, Stark county, State of Ohio, have invented and produced a new and original Design for a Standard for Plows, of which the following is a specification.

In the drawings, Figure 1 is an elevation of one side of the standard. Fig. 2 is a view ⁵ from the opposite side. Fig. 3 is a rear view.

My invention relates to an original design for a plow-standard adapted to be used with an independent plow-beam.

The design resides in the surface and outline configuration of the standard. The upper part of the standard A has a flaring top, as at a, and projecting from the horizontal surface of the standard-top is a bolt a. As shown in Figs. 1 and 3, the front edge of the standard in the left of Fig. 3 projects, as at c, while in rear of this projection there is a recess d. A ledge e borders the lower edge of the recess d and overhangs the under part of the standard. This under or lower part is ¹⁵ shown at B and has a border f surrounding

a central recessed part g. On the opposite face (shown in Fig. 2) the front edge is made in a succession of curves h i k, while the body of the standard from the top to the bottom, as shown at C, curves downwardly, gradually ³⁰ increasing in width to the point m, and from thence forward to the point the width decreases. Fig. 3 shows the part B in edge view and the outward flare of the part C with the web. As seen in Figs. 1 and 2, the curved ³⁵ front and rear edges incline but slightly to the rear, and the general direction in which the standard extends from the ground is vertical, and this, together with the flat upper surface with the projection extending upwardly therefrom, forms the characteristic features of the design.

I claim—

The design for a plow-standard herein shown and described.

GEORGE W. REAM.
